UNITED STATES PATENT OFFICE.

PAOLO PORTA, OF MILAN, ITALY, ASSIGNOR TO MICHELE UDA AND MARY BELLA SCOTT UDA, OF SAME PLACE.

IMPROVEMENT IN BRIDGE-LADDERS.

Specification forming part of Letters Patent No. 155,751, dated October 6, 1874; application filed March 25, 1874.

To all whom it may concern:

Be it known that I, PAOLO PORTA, of the city of Milan, Kingdom of Italy, have invented a new and useful Improvement in Bridge-Ladders or Flying Bridges; and declare the following to be a full, clear, and exact description thereof, as will enable others skilled in the art to which it pertains to make and use it, reference being had to the accompanying drawings, which make a part of this specification.

My invention relates to an improvement in bridges, which I term a bridge-ladder or flying bridge, in contradistinction to such bridges as require pier-support; and consists of the combination of devices and appliances, as hereinafter specified and claimed, consisting essentially of a truck, to which is pivoted and attached the lower section of the bridgeway, to which are added other sections of the same by suitable joining and bracing device, and the whole so adjusted and arranged by suitable mechanism that, by the operation of said mechanism, my device can be used either for the purpose of a bridge, or can be raised to any desired angle, and made self-supporting by the system of adjustable counterpoise-weights and other devices, as will hereinafter more fully appear.

In the drawings, Figure 1 is a side elevation of my invention; Fig. 2, a longitudinal section of the same.

A is the bed of a truck, at the rear part of which is pivoted the lower section B of the bridge. This section has a rigid lever-arm, B', projecting at an angle toward the rear, which bears the roller C at its extremity. A shaft or roller, D, placed upon the truck A, in front of the pivot b, is provided with a gear-wheel, e, that engages with the pinion D¹ on the end of the crank-shaft D². I do not, however, limit myself to this method of operating the shaft or roller D, as any suitable equivalent mechanism may be employed for the purpose. One or more lines, E, pass down beneath the roller F, attached to the lower end of the descending brace F' at the rear of the truck A; thence up to the roller C, and down again to the truck-bed, to which they are securely at-

tached. E' are lines passing from the extremity of each section of the bridge over uprights Z, placed upon the forward portion of the truck A, and from thence downward over pulley e, placed at the rear and lower portion of the truck A, and from thence forward, where they are attached to suitable winding shafts or rollers e² in the forward portion of the truck-bed. The rollers or shafts e² are provided with suitable crank or gearing device. Y is a straining-line attached to the extremity of the second added section of the bridgeway, passing from thence over the roller C of the angular lever-arm B'; from thence downward around the pulley F of the descending brace F', and thence forward, where it is attached to a suitable roller or shaft, y, operating in the truck-bed A, and operated by suitable crank or gearing arrangement. The uprights Z upon the truck A, when in use, are suitably braced to withstand the strain put upon them. At their bases they are divided, but provided with the hinge z upon their rear face, and the locking device z' upon their anterior face, so that when not in use they may be unlocked and turned backward upon the supports z'. To counteract any tendency to tip forward, the truck A is provided with suitable sliding or adjustable counterpoise-weights G, and, when necessary, the extra counterpoise-weights G', swung upon the bars g, which are fixed and braced to the truck A. When my bridge is ready for use, as shown in Fig. 1, the brace-rods K K' K² K³ L, with their intermediate posts L', form a rigid and steady truss-support.

The construction of the various parts of my bridgeway will be readily understood by reference to the drawings.

The posts L' are situated at or near the ends of each section of the bridgeway, and the straining-rod K extends from the exterior end of each to the base of the next succeeding one, while a tie-rod, K¹, in sections, unites the ends of all. The lever-arm B' of the base-section is strongly secured by the straining rods or bars K² K³ L. It will be seen that the strains are all strains of extension, excepting those on the posts and upon the ways, which in both instances are longitudinal strains of compres-

sion. The strains are, therefore, all communicated directly to the base section, and all tendency to sag is avoided, and the materials subjected to those strains which they are most capable of resisting. I propose to provide one or more extra straining-rod, O, extending from the top of the posts L' to the middle portions of the way-sections, and acting in the same capacity as the rods K. The ends of the way-sections are provided with strap-loops b', and are halved, mortised, or otherwise shaped so as to fit upon each other, and permit the key-bar M to be inserted. Other devices for uniting the sections and the tie-rods may be employed; but the devices shown are simple and effective. The truck is provided with suitable running-gear and devices for braking and fixing the carriage rigidly in any desired place. The posts L' are provided at their bases and upper extremities with the spurs j¹, over which are slipped the extremities of the connecting tie-rods and straining-rods, and are provided with the pins or keys j² for securing the same.

My invention is susceptible of a double use, viz., of a bridge, as before described, and of a portable signal-lookout. The latter may be accomplished by unshipping the lines E' and operating the shaft or roller D. This winds the cords E upon the shaft or roller D, and, by shortening the distance between the rollers C and F, brings the lever-arm B' down and carries the section B, with all its attached sections, upward to any desired angle, as shown in my device for firemen's ladder, for which patent No. 142,349 of the United States, dated September 2, 1873, was granted to me. In this condition the bridgeway is transformed into a ladder, at the top of which may be fixed any suitable platform or cage, from which observations may be taken. I have provided on the forward portion of the truck-bed A the shaft I, with its line. This is to be used when the bridge is transformed into a signal-lookout, for the purpose of hoisting the platform or observatory to the top of the elevated ladder by passing the line of the shaft I upward and

through suitable pulley arrangement fixed to upper section of the ladder. It is also provided with suitable hooks and rests p, or other devices for depositing and carrying tie-rods, extra counterpoise-weights, removable braces, and other of the smaller detachable portions of the bridge, when said bridge is not in use, or is being transported from one place to another. When not in use all the sections of the bridgeway, with their bracing-rods and lines, are detached and placed upon the truck A, in which condition it will be seen that the entire structure is easily portable.

The operation is as follows: The bridgeway is made to any desired length by the addition of a requisite number of sections thereto, which are adjusted in a horizontal position. The sections are then raised by depressing the rigid arm of the base-section through its mechanism. In this elevated position the structure is moved to the bank of the stream to be crossed, when the bridge is lowered to the opposite bank. By my provision I am enabled to swing my bridge to an opposite bank of a different altitude from that on which the truck A stands. When the bridgeway has been lowered the operating parties go out upon the same and adjust the suspension-cords in their proper position, after which they are made taut by their proper rollers, and act to sufficiently sustain the bridge.

What I claim is—

The combination, with a self-supporting ladder and counterpoised portable truck, A, as described and shown, of adjustable uprights Z and adjustable suspension-cables E E', whereby said ladder may be readily transformed into a bridge, substantially as shown and described.

In testimony that I claim the foregoing I have hereunto set my hand and seal this 6th day of March, 1874.

PAOLO PORTA. [L. S.]
